(57) CLAIM

The ornamental design for a face mask as shown and described.

DESCRIPTION

FIG. 1 is a front perspective view of a face mask, in accordance with my new design.

FIG. 2 is a front view of the face mask in accordance with the new design.

FIG. 3 is a rear view of the face mask in accordance with the new design.

FIG. 4 is a right side view of the face mask in accordance with the new design.

FIG. 5 is a left side view of face mask in accordance with the new design.

FIG. 6 is a top view of the face mask in accordance with the new design.

FIG. 7 is a bottom view of the face mask in accordance with the new design; and,

FIG. 8 is a front perspective view of the face mask as worn in accordance with the new design.

The broken lines depict portions of the face mask that form no part of the claimed design. The broken line showing of an adult person in FIG. 8 depicts environment and forms no part of the claimed design. The surface(s) or portion(s) of the claimed design that would normally be visible but are not shown in the drawings or described in the Specification of the present application form(s) no part of the claimed design.

1 Claim, 8 Drawing Sheets
